YARN BOBBIN

Glen W. McCollough, La Jolla, Calif.

Application August 2, 1954, Serial No. 447,029

5 Claims. (Cl. 242—125)

The present invention relates generally to bobbins and more particularly to a yarn bobbin.

The primary object of this invention is to provide a yarn bobbin comprising a simple tubular element having an angularly cut end which, when the bobbin is threaded correctly, prevents the yarn from unwinding except when the yarn is intentionally released.

Another object of this invention is to provide a yarn bobbin which is extremely compact and is ideally suited for use when knitting with yarns of several colors, with a separate bobbin being used to hold each color of yarn.

Another object of this invention is to provide a yarn bobbin which may be used with a loom as well as in knitting done by hand.

Another object of this invention is to provide a yarn bobbin which is adapted for fabrication from many different materials, so that the choice of material can be according to the dictates of availability and price considerations, the exact sizes and proportions being matters easily determined to suit particular conditions and needs.

Another object of this invention is to provide a yarn bobbin which is inexpensive and practicable to manufacture.

Finally, it is an object to provide a yarn bobbin of the aforementioned character which is simple and convenient to use, and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawing which forms a material part of this disclosure and wherein similar characters of reference indicate similar or identical elements and portions throughout the specification and throughout the views of the drawing, and in which:

Fig. 1 is a perspective view of the bobbin wound and threaded with a quantity of yarn.

Fig. 2 is a longitudinal sectional view thereof taken on the line 2—2 of Fig. 1.

Fig. 3 is a partially sectioned, fragmentary, side elevation view of the bobbin with an end ring secured thereon.

Referring now to the drawing in detail, the bobbin 10 comprises a tubular spool portion or body 12 having an obliquely angularly profiled end 14. The body 12 may be of any suitable cross sectional shape according to needs, certain shapes being more suitable than others for particular purposes, that illustrated being circular in cross section. The body 12 may be made from various materials, plastic being ideal for hand knitting or the like and when the bobbin is to be used with a loom it can be weighted or constructed from a heavier material such as any suitable metal.

To use the bobbin 10, a quantity of yarn 16 is wound around the body 12 in the normal manner, the free end 18 thereof being threaded through the yarn receiving bore 19

2

of said body from the obliquely profiled end 14 and looped over the end so that the portion 20 of a loop 22 engages the obliquely profiled end 14 which is elliptical in form. When the free end 18 is pulled taut, or the bobbin is suspended on the yarn, the portion 20 of the loop 22 quickly seeks the part 24 of the profiled end 14 which is closest to the wound part of the yarn with the result that the yarn binds or locks against further unwinding. Thus the yarn 16 is prevented from unwinding from the bobbin 10 until intentionally released. This is accomplished by grasping the loop 22 of the yarn and pulling the required length of yarn free, the slack then being pulled through the yarn receiving bore 19 until the yarn once more binds on the angularly profiled end 14.

If desired the bobbin may be constructed as shown in Fig. 3, in which the obliquely profiled end 14 is fitted with an end ring 26 adapted to increase the coefficient of friction between the portion 20 and the bobbin. This ring may be of resilient material such as rubber, plastic or the like. This end ring 26 provides considerable frictional surface on which the portion 20 tends to bind.

The bobbin may be made in various sizes according to requirements, an ideal size for hand knitting being approximately 2 1/4 inches in length, for example. Further, both ends of the body 12 may be angularly cut if desired, since this may cheapen the manufacture of the bobbin, and it is also conceived that the end 14 may be modified to present a more or less sharply angulated profile and that the end 14 may be notched if desired.

The operation of this invention will be clearly comprehended from a consideration of the foregoing description of the details thereof, taken in connection with the drawing and the above recited objects. It will be obvious that all said objects are amply achieved by this invention.

Further description would appear to be unnecessary. It is understood that minor variation from the forms of the invention disclosed herein may be made without departure from the spirit and scope of the invention, and that the specification and drawing are to be considered as merely illustrative rather than limiting.

I claim:

1. A yarn bobbin comprising an elongated, thin-walled, hollow cylindrical body completely open at both ends and having one end lying in a single plane extending at an oblique angle to the longitudinal axis of the body and having an elliptical form, said body constituting a spool onto which coils of yarn may be wound externally, the hollow body constituting a channel for the free end portion of the yarn which in use is looped over said one end, and said one end, by virtue of its elliptical form, constituting means for automatically guiding the yarn looped thereover toward that point of said one end closest to said coils, thereby preventing unwanted unwinding.

2. A yarn bobbin comprising an elongated, thin-walled, hollow, recti-cylindrical body completely open at both ends and having at one end an elliptical edge lying in a single plane extending obliquely angular relative to the longitudinal axis of the body, and means to resist slippage of yarn over one side of said elliptical edge.

3. A yarn bobbin comprising an elongated tubular, thin-walled body having a spool portion on which yarn may be externally wound, at least one end of said body being obliquely angular with respect to the longitudinal axis of the body and having an elliptical form with one portion thereof defining a sharp edge extending toward said axis to resist slippage of yarn engaged therewith.

4. A yarn bobbin comprising an elongated tubular, thin-walled body having a spool portion on which yarn

may be externally wound, said body being open at both ends, at least one end of said bobbin being elliptical having an end ring fixed thereto, said end ring being of soft material to resist slippage of a strand of yarn looped thereover.

5. A bobbin according to claim 1 and including an end ring of soft material fixed to said one end.
